UNITED STATES PATENT OFFICE.

ELIJAH D. PARROTT, OF PORTLAND, OREGON.

CARBURETER.

No. 840,708.

Specification of Letters Patent.

Patented Jan. 8, 1907.

Application filed November 3, 1905. Serial No. 285,754.

To all whom it may concern:

Be it known that I, ELIJAH D. PARROTT, a citizen of the United States, residing at Portland, in the county of Multnomah and State 5 of Oregon, have invented a new and useful Carbureter, of which the following is a specification.

This invention relates to carbureters, and has for its principal object to provide a device of simple construction by which air may be thoroughly saturated with hydrocarbon or a previously-formed gas may be enriched in carbon.

A further object of the invention is to provide a carbureter in which low-grade hydrocarbon may be successfully employed by providing means for atomizing or spraying the liquid.

A still further object of the invention is to provide a carbureter in which the air is passed through a casing or tank containing hydrocarbon in an atomized state or in the form of a fine spray, so that it may be readily absorbed by the air.

A still further object of the invention is to provide a carbureter which includes means for reducing the oil to the form of a spray or to provide means whereby the carbureting chamber or tank will be completely filled 30 with hydrocarbon in an atomized state.

A still further object of the invention is to provide a carbureter in which means are employed for agitating and mingling a volume of air with atomized hydrocarbon.

A still further object of the invention is to provide a simple but effective means for reducing the liquid hydrocarbon to the form of a spray, and, further, to construct a device in which a very small quantity of oil may be 40 successfully employed in carbureting a large volume of air.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, 45 proportions, size, and minor details of the structure may be made without departing from the spirit or sacrificing any of the advantages of the invention.

In the accompanying drawings, Figure 1 is 55 a vertical section of a carbureting device constructed in accordance with the invention.

Fig. 2 is a transverse sectional view of the same on the line 2 2 of Fig. 1. Figs. 3 and 4 are sectional views illustrating slightly-modified constructions of the carbureter. 60

Similar numerals of reference are employed to indicate corresponding parts throughout the several figures of the drawings.

In carrying out the invention a casing 10 of cylindrical form is mounted on a suitable base 11 and is connected by a pipe 12 to a supply-tank 13, filled with the hydrocarbon to be employed. The pipe 12 extends within the lower portion of the casing and is provided with a float-operated valve 14, which is opened and closed in accordance with the level of liquid within the casing 10, the object of the float being to maintain a constant level within said casing. 70

The casing is provided with bearings for the reception of a transversely-disposed shaft 15, that is arranged somewhat below the exact center of the casing. This shaft is provided at one end with a gear 16 or similar member, that may be driven in any suitable manner. 75

To the central portion of the shaft is secured a hub 17, provided with diametrically-opposed hollow arms 18, that are arranged to receive revoluble spraying members 19, the stems 20 of said spraying members being arranged within the hollow arm and held in any desired position of adjustment by set-screws 21. The revoluble spraying members 19 are in the form of brooms or brushes, each comprising a bunch of resilient strands or bristles formed of wire, broom-straw, bristles, strips of metal, wood, or other material, which when dipped into the body of liquid 95 in the bottom of the casing will carry up a small quantity of such liquid.

The casing is provided with a plurality of transversely-extending bars 22, which are disposed in the path of movement of the spraying devices 19, and the end portions of the resilient member come into contact with said bar and are retarded thereby, such resilient members being allowed to escape gradually from contact with the bar, and the sudden release of said members effecting the discharge of the liquid hydrocarbon in the form of drops or in the form of a spray. The bars are arranged at frequent intervals, and any desired number of movable spraying members 19 may be employed; but in all cases the contact of the movable spraying 110

member with the fixed bar or similar retarding device will result in the discharge of the liquid practically in atomized form, so that the entire chamber is filled with liquid in 5 finely-divided form, and air passing therethrough will be thoroughly saturated.

The air or gas to be enriched enters the casing through a port 25 and discharges through a port 26; but in order to prevent 10 the direct flow of a current of air between the two ports the shaft 15 is provided with radially-disposed blades or paddles 27, which as they revolve will act to mix a volume of air with the finely-divided hydrocarbon, so 15 that the air will take up the liquid to its fullest capacity.

Arranged in the upper portion of the casing are bearings for the support of a horizontally-disposed shaft 30, on which is 20 mounted a fan 31, the fan being disposed adjacent to the air-inlet port 25. At one end of the shaft is arranged a belt-wheel 32, over which passes a belt 33, that is driven by a large belt-wheel 34 on the main shaft 15, so 25 that the fan will be revolved very rapidly and will force a current of air to travel around the interior of the casing. The fan serves also to prevent the direct passage of a current of air between the inlet and the outlet 30 ports and is effective in intermingling the air and atomized liquid.

In some cases the revoluble spraying devices may be in the form of brushes 19', mounted on an annulus 40 and arranged to 35 dip into the liquid, and thence pass into engagement with stationary bars 22', by means of which the liquid is removed from the sprayers in finely-divided form. The construction shown in Fig. 4 illustrates a further modification, wherein the spraying 40 element is in the form of a revoluble brush 19^a, that is arranged to dip into the hydrocarbon and thence pass into contact with a bar or plate 22^a for the purpose of discharging 45 the hydrocarbon in atomized form.

With a device constructed in accordance with this invention the lowest grades of hydrocarbon may be successfully employed

for carbureting air or gas, and a comparatively small amount of hydrocarbon may be 50 used in treating a relatively large volume of air.

Having thus described the invention, what is claimed is—

1. In a carbureter, a casing arranged to 55 contain a body of hydrocarbon, a shaft, an arm carried thereby, a spraying member adjustable on said arm, and a plurality of rigid bars disposed in the path of movement of said spraying member. 60

2. In a carbureter, a casing arranged to contain a body of liquid hydrocarbon, a movable shaft, hollow arms carried thereby, spraying members having stems arranged within said hollow arms, means for locking 65 said stems in adjusted position, and a plurality of spaced bars carried by the casing and forming obstructions in the path of movement of the spraying devices.

3. In a carbureter, a casing having inlet 70 and discharge ports and arranged to contain a body of hydrocarbon, a revoluble shaft, spraying members carried by the shaft, bars arranged in the path of movement of the spraying members, agitating-blades carried by the shaft, and an auxiliary fan arranged adjacent to the inlet-port and serving to direct a current of air around the interior of the casing. 75

4. In a carbureter, a casing having inlet 80 and discharge ports and arranged to contain a body of hydrocarbon, a revoluble shaft, spraying members and agitating-blades both carried by said shaft, and means for engaging the spraying members during the rotative 85 movement of the latter to effect the discharge of the hydrocarbon in the form of a spray.

In testimony that I claim the foregoing as my own I have hereto affixed my signature 90 in the presence of two witnesses.

ELIJAH D. PARROTT.
